Filed Dec. 21, 1956, Ser. No. 629,863

9 Claims. (Cl. 333—97)

This invention relates to coaxial connectors and more particularly to a coaxial connector for use with rigid or semi-rigid gas dielectric coaxial lines.

In most applications, where coaxial connectors are utilized at relatively normal temperatures, the matching problem between the gas dielectric line and the connector is not very difficult because a material which has a relatively low dielectric constant can be used to support the center conductor in the connector. In applications, however, such as where the connector is to be used in a missile, where temperatures as high as 600° F. may be encountered, it is necessary that a material which will stand these temperatures be used for the center conductor support. It has been found that certain high temperature ceramics will best satisfy such requirements. Such ceramics, however, all have high dielectric constants (in excess of 6). In order to achieve coupling of a radio frequency signal from a gas dielectric line to a connector with a center conductor support of relatively high dielectric constant without intolerable reflections, it is necessary that some special matching means be utilized. The device of this invention offers a solution to this problem. This is accomplished by specially shaping the support beads and associated portions of the connector so that the transition angles at dielectric boundary surfaces effect reflectionless transmission.

With the device of this invention it is possible to transfer ultra high frequency radio energy with a voltage standing wave ratio of less than 1.2 and a loss of less than .5 db when operating into a matched load. This can be accomplished while utilizing separator beads fabricated of high temperature ceramics which have dielectric constants in excess of 6. In addition to its excellent matching and high temperature characteristics, the device of this invention is such that it remains airtight when utilized with pressurized lines. It is therefore an object of this invention to provide an improved coaxial connector for use with rigid or semi-rigid gas-filled lines.

It is another object of this invention to provide a coaxial connector which will function satisfactorily at very high temperatures.

It is a further object of this invention to provide a coaxial connector which will couple radio frequency signals with little or no reflections.

It is a still further object of this invention to provide a coaxial connector for use with gas-filled lines which is airtight and can be utilized successfully with pressurized lines.

It is a still further object of this invention to provide a radio frequency coaxial connector for use at high temperatures which has low loss and good transmission characteristics over a broad frequency range.

It is still another object of this invention to provide an easily detachable connector that will operate at high temperatures with little or no reflections.

Other objects of this invention will become apparent from the following description taken in connection with the accompanying drawings in which

2

Fig. 1 is an illustration of a male version of the device of this invention;

Fig. 2 illustrates a cross section of a male version of the device of this invention represented as cut by a plane 2—2 indicated in Fig. 1;

Fig. 3 illustrates a female version of the device of this invention;

Fig. 4 illustrates a cross section of a female version of the device of this invention represented as cut by a plane 4—4 indicated in Fig. 3;

Fig. 5 is a diagram illustrating the angles at the dielectric boundary surfaces in the device of this invention; and

Fig. 6 illustrates wave travel in the device of this invention.

Referring to Figs. 1 and 2, a male version of the connector as utilized with a gas dielectric coaxial line is shown. The connector consists of an electrically conductive shell 1 with an inner center electrical conductor 4 to form a coaxial line. The center conductor is supported by two conical beads 3a and 3b which are fabricated of a high temperature ceramic. A mica bonded glass such as Mycalex which will stand temperatures in excess of 600° F. is satisfactory. There is a gas dielectric in the spaces 6a, 6b and 6c between the center conductor, ceramic beads and outer shell. This gas can be air or any other suitable gas and can be either pressurized or not depending on insulation breakdown requirements.

The ceramic beads are bonded to the outer concentric shell at points 8a and 8b and to the center conductor 4 at points 7a and 7b. A high temperature porcelain cement or enamel such as Sauereisen 19 fabricated by the Sauereisen Company, Pittsburgh, Pennsylvania is recommended. To assure a good and durable bond under high temperature operating conditions, it is necessary that such a bonding agent be cured by heating under vacuum.

Referring to Fig. 5, in which a boundary surface 16 between the support beads and a gas dielectric is illustrated, the angle 18 at which the incident wave (that coming from the left hand side in the diagram) enters the dielectric boundary surface is referred to as θ_1 . To assure that signals will pass through the dielectric transition with little or no reflection, the conical beads must be so shaped that θ_1 satisfies the equation,

$$\theta_1 = \text{arc tan } \sqrt{\frac{K_2}{K_1}} \quad (1)$$

where K_2 is the dielectric constant of the material which the wave is entering, and K_1 is the dielectric constant of the material which the wave is leaving. θ_1 is the angle of incidence and θ_2 the angle of refraction 19. If the wave, as is indicated in Fig. 5, is polarized in the plane of incidence, and θ_1 satisfies Equation (1), the wave will be refracted at the dielectric boundary at an angle θ_2 with little or no reflection. This phenomenon is known in the art as the "Brewster Angle" effect and is discussed in the RCA Review, volume 15, pp. 238-251 in an article entitled, "Application of Brewster's Angle to the Design of Coaxial Line Components for Microwaves" by B. A. Dahlman.

Referring to Fig. 6, the path of an electrical wave through the connector is illustrated. The direction of wave travel is perpendicular to the mutually perpendicular electric (E) and magnetic (H) fields. As can be seen, the wave enters from the gas dielectric at the left with an angle of incidence 18a. It is refracted with an angle of refraction 19a as it enters the first ceramic separator bead 3a. An equal and opposite refraction occurs as it leaves the ceramic medium with an angle of incidence 18b and an angle of refraction 19b. This process is repeated as the wave enters and leaves the second separator

beads 3b with incident angles 18c and 18d refraction angles 19c and 19d.

Equation (1) will be satisfied if the conical beads are shaped so that the tangents of their base angles 20a and 20b are equal to

$$\sqrt{\frac{K_2}{K_1}}$$

where K_2 is the dielectric constant of the material of the beads and K_1 is the dielectric constant of the gas (which for all practical purposes is unity). This can be shown by proving with simple geometry that the tangents of the base angles of the beads are equal to those of the angles of incidence, θ_1 . The angle 21 is the complement of the angle of incidence 18c in entering the second separator bead 3b. Angle 22 is equal to angle 21. Since the base angle 20b of the conical bead is the complement of angle 22, this base angle must be equal to the angle of incidence, 18c. The base angle 20a of the first bead 3a is equal to angle 20b and will give an angle of incidence 18a which has a tangent equal to that of angle 20b.

Still referring to Fig. 6, it is also necessary that the impedance of the conical transmission lines formed between the outer conductor 1 at surfaces 8a and 8b and the inner conductor 4 at surfaces 7a and 7b respectively, with the conical separator beads as the dielectric in between, be matched to the characteristic impedance of the coaxial line being coupled. Such an impedance match can be accomplished by proper choice of the face angles ϕ_a (14a and 14b) at the junction of the conical beads with the center conductor, and the face angles, ϕ_b (13a and 13b) at the junction of the connector beads with the retaining surfaces in the concentric shell. These faces angles are referenced from the longitudinal axis of the center conductor as indicated in Fig. 6, and are determined by the relationship,

$$Z_c = \frac{60}{\sqrt{K_2}} \ln \frac{\tan \frac{\phi_b}{2}}{\tan \frac{\phi_a}{2}} \quad (2)$$

where Z_c is the characteristic impedance of the conical and coaxial lines to be matched, and K_2 is the dielectric constant of the material of the conical separator beads.

While in practice the characteristic impedance of the conical line can be made to approach the characteristic impedance of the coaxial line to be coupled, it is in some instances difficult to achieve a perfect match. In the device illustrated in Fig. 2, the face angle ϕ_b (13a and 13b, Fig. 6) were made equal to 90° instead of the theoretical 105° to facilitate fabrication. To compensate for shunt capacitance due to slight mismatch caused by such practical design, an undercut 5 is made in the shell. An effective inductance determined by the length and depth of this undercut is thus provided to compensate for such shunt capacitance. The dimensions of this undercut can best be determined experimentally for any specific connector by the "cut and try" method.

Referring to Fig. 2, coupling nut 9 is used to secure the connector to its female counterpart. Pin 15 makes connection with a mating receptacle 22 (Fig. 4) on the female connector. Gasket 10 provides a seat for the outer shell of the female connector. A cylindrical metal ferrule 11 is used to form an airtight connection between coaxial line 2 and the connector. The ferrule is tapered on both ends so that it will seat itself against the retainer ring 23 on one end and the sleeve nut 12 on the other. This ferrule is bonded to the very end of the outer conductor of the coaxial line by brazing or similar means. It is then fastened to the connector by means of a sleeve nut 12. To assure a good airtight connection, approximately 125 inch lbs. of torque is applied to this nut in tightening it. The center conductor 4 has a hollow receptacle on its end to receive the center conductor 21 of the coaxial line.

4
A female version of this connector is illustrated in Figs. 3 and 4. Construction is similar to that of the male type shown in Figs. 1 and 2 in all respects except that provision is made to mate it with its male counterpart, as is obvious in the illustrations.

Practical embodiments of the devices illustrated in Figs. 1, 2, 3, and 4 have been successfully tested. These have conical beads of supramica #555, a mica bonded glass with a dielectric constant of 9.3, fabricated by the Mycalex Corp., Clifton, New Jersey. The base angles of these beads (Fig. 6, 20a and 20b) are equal to 71°51'. The face angles, ϕ_a (Fig. 6, 14a and 14b) are equal to 14°7'. The face angles, ϕ_b (Fig. 6, 13a and 13b) are equal to 90°.

15 The device of this invention can be used at frequencies through the ultra high frequency range with low losses and insignificant standing wave ratio when properly matched to the coaxial line it is utilized with. Utilizing ceramic separators in this fashion provides a connector which will function at temperatures in excess of 600° F.

20 Although this invention has been described and illustrated in detail, it is to be clearly understood that the same is by way of illustration and example only, and is not to be taken by way of limitation, the spirit and scope 25 of this invention being limited only by the terms of the appended claims.

We claim:

30 1. In a coaxial electrical connector for use with gas dielectric coaxial lines, a center electrical conductor, an electrically conductive shell concentric with and surrounding said center conductor, a gas dielectric interposed between said center conductor and said shell, and a pair of hollow conical ceramic separator beads, said beads being identical as to dielectric constant, base angle, face angle formed with said center conductor, and face angle formed with said shell, said separator beads being concentric to said center conductor, the vertex ends of said beads facing each other and being bonded to adjacent sections of said center conductor, and the base ends of said beads being bonded to the inner wall of said concentric shell.

35 2. In a coaxial electrical connector for use with gas dielectric coaxial lines, a center electrical conductor, an electrically conductive shell concentric with and surrounding said center conductor, a gas dielectric interposed between said center conductor and said shell, and a pair of hollow conical ceramic separator beads, said beads being identical as to dielectric constant, base angle, face angle formed with said center conductor, and face angle formed with said shell, said separator beads being concentric to said center conductor, the vertex ends of said beads facing each other and being bonded to adjacent sections of said center conductor, the base ends of said beads being bonded to the inner wall of said concentric shell, the base angles of said conical beads being equal to each 55 other and satisfying the relationship,

$$\theta_1 = \text{arc tan } \sqrt{\frac{K_2}{K_1}}$$

60 where θ_1 is equal to the base angles of said beads, K_2 is the dielectric constant of the material of said beads and K_1 is the dielectric constant of said gas dielectric.

65 3. In a coaxial electrical connector for use with gas dielectric coaxial lines, a center electrical conductor, an electrically conductive shell concentric with and surrounding said center conductor, a gas dielectric interposed between said center conductor and said shell, a pair of hollow conical ceramic separator beads, said beads being identical as to dielectric constant, base angle, face angle formed with said center conductor and face angle formed with said shell, said separator beads being concentric to said center conductor, the vertex ends of said beads facing each other and being bonded to adjacent sections of said center conductor, the base ends of said beads being bonded to the inner wall of said concentric shell, the 70 75

base angles of said conical beads being equal to each other and satisfying the relationship,

$$\theta_1 = \arctan \sqrt{\frac{K_2}{K_1}}$$

where θ_1 is equal to the base angles of said beads, K_2 is the dielectric constant of the material of said beads and K_1 is the dielectric constant of said gas dielectric, a cylindrical electrically conductive ferrule adapted to be bonded to a tubular electrical conductor, and means for urging said ferrule against the end of said concentric shell in gas tight relationship thereto.

4. In a coaxial electrical connector for use with gas dielectric coaxial lines, a center electrical conductor, an electrically conductive shell concentric with and surrounding said center conductor, a gas dielectric interposed between said center conductor and said shell, and a pair of hollow conical ceramic separator beads, said beads being identical as to dielectric constant, base angle, face angle formed with said center conductor, and face angle formed with said shell, said separator beads being concentric to said center conductor, the vertex ends of said beads facing each other and being bonded to adjacent sections of said center conductor, the base ends of said beads being bonded to the inner wall of said concentric shell, the base angles of said conical beads being equal to each other and satisfying the relationship,

$$\theta_1 = \arctan \sqrt{\frac{K_2}{K_1}}$$

where θ_1 is equal to the base angles of said beads, K_2 is the dielectric constant of the material of said beads and K_1 is the dielectric constant of said gas dielectric, the face angles of the junction of said conical beads with said center conductor and said conical beads with said concentric shell as referenced from the longitudinal axis of said center conductor satisfying the relationship,

$$Z_0 = \frac{60}{\sqrt{K_2}} \ln \frac{\tan \frac{\phi_b}{2}}{\tan \frac{\phi_a}{2}}$$

where Z_0 is any desired characteristic impedance, K_2 is the dielectric constant of the material of said conical beads, ϕ_a is the face angle formed between said conical beads and said center conductor and, ϕ_b is the face angle formed between said conical beads and said concentric shell.

5. In a coaxial electrical connector for use with gas dielectric coaxial lines, a center electrical conductor, an electrically conductive shell concentric with and surrounding said center conductor, said concentric shell having an undercut surface on its inner wall to provide an effective inductance, a gas dielectric interposed between said center conductor and said shell, a pair of hollow conical ceramic separator beads, said beads being identical as to dielectric constant, base angle, face angle formed with said center conductor and face angle formed with said shell, said separator beads being concentric to said center conductor, the vertex ends of said beads facing each other and being bonded to adjacent sections of said center conductor, the base ends of said beads being bonded to the inner wall of said concentric shell, the base angles of said conical beads being equal to each other and satisfying the relationship,

$$\theta_1 = \arctan \sqrt{\frac{K_2}{K_1}}$$

where θ_1 is equal to the base angles of said beads, K_2 is the dielectric constant of the material of said beads and K_1 is the dielectric constant of said gas dielectric, a cylindrical electrically conductive ferrule adapted to be bonded to a tubular electrical conductor, and means for urging said ferrule against the end of said concentric shell in gas tight relationship thereto.

6. In a coaxial electrical connector for use with gas dielectric coaxial lines, a center electrical conductor, an electrically conductive shell concentric with and surrounding said center conductor, said concentric shell having an undercut surface in its inner wall to provide an effective inductance, a gas dielectric interposed between said center conductor and said shell, a pair of hollow conical ceramic separator beads, said beads being identical as to dielectric constant, base angle, face angle formed with said center conductor, and face angle formed with said shell, said separator beads being concentric to said center conductor, the vertex ends of said beads facing each other and being bonded to adjacent sections of said center conductor, the base ends of said beads being bonded to the inner wall of said concentric shell, the base angles of said conical beads being equal to each other and satisfying the relationship,

$$\theta_1 = \arctan \sqrt{\frac{K_2}{K_1}}$$

20 where θ_1 is equal to the base angles of said beads, K_2 is the dielectric constant of the material of said beads and K_1 is the dielectric constant of said gas dielectric, the face angles at the junction of said conical beads with 25 said center conductor and said conical beads with said concentric shell as referenced from the longitudinal axis of said center conductor satisfying the relationship,

$$30 Z_0 = \frac{60}{\sqrt{K_2}} \ln \frac{\tan \frac{\phi_b}{2}}{\tan \frac{\phi_a}{2}}$$

where Z_0 is any desired characteristic impedance, K_2 is the dielectric constant of the material of said conical beads, ϕ_a is the face angle formed between said conical beads and said center conductor and, ϕ_b is the face angle formed between said conical beads and said concentric shell, a cylindrical electrically conductive ferrule adapted to be bonded to a tubular electrical conductor, and means for urging said ferrule against the end of said concentric shell in gas tight relationship thereto.

- 40 7. In a coaxial electrical connector for use with gas dielectric coaxial lines, a center electrical conductor, an electrically conductive shell concentric with and surrounding said center conductor, said concentric shell having an undercut surface in its inner wall to provide an effective inductance, air interposed as a dielectric between said center conductor, and said shell, and a pair of hollow conical separator beads fabricated of mica bonded glass 45 having a dielectric constant of substantially 9.3, said beads being identical as to dielectric constant, base angle, face angle formed with said center conductor, and face angle formed with said shell, said separator beads being concentric to said center conductor, the vertex ends of said beads facing each other and being bonded to adjacent sections of said center conductor, the base ends of said beads being bonded to the inner wall of said concentric shell, the base angles of said beads being substantially 50 equal to 72° , the face angles of the junction of the vertex ends of said beads with said center conductor as measured from the longitudinal axis of said center conductor being substantially equal to 14° , the face angles of the junction of the base ends of said beads with said shell as measured from the longitudinal axis of said center conductor being substantially equal to 90° .

- 55 8. In a coaxial electrical connector, a center electrical conductor, an outer conductive shell concentric with said center conductor, a gas dielectric interposed between said inner and outer conductors, and a pair of hollow conical ceramic separator beads, said beads being identical as to dielectric constant, base angle, face angle formed with said center conductor, and face angle formed with said shell, said conical beads having base angles whose magnitude is a function of the dielectric constant of the bead 60 ceramic material, said separator beads being concentric

to said center conductor, the vertex ends of said beads facing each other and being bonded to adjacent sections of said center conductor, the base ends of said beads being bonded to the inner wall of said concentric shell.

9. The device as recited in claim 8 wherein the magnitudes of the face angles between said beads and said center conductor and said beads and said outer conductor are a function of the dielectric constant of the ceramic material of said beads.
